UNITED STATES PATENT OFFICE

97,523

DESIGN FOR A WOVEN MESH CLOTH

Louise Barnes Gallagher, New York, N. Y.

Application August 3, 1935, Serial No. 57,937

Term of patent 3½ years

To all whom it may concern:

Be it known that I, Louise Barnes Gallagher, a citizen of the United States and a resident of New York city, county and State of New York, have invented a new, original, and ornamental Design for Woven Mesh Cloth, of which the following is a specification, reference being had to the accompanying drawing, forming part thereof.

In the drawing,

Figure 1 is a plan view of the woven mesh cloth showing my new design.

Figure 2 is a plan view of a piece of woven mesh cloth shown in Fig. 1, enlarged approximately 50% making it one and one half times larger than the mesh in Fig. 1, bringing out the details of the design namely the grouping of the several threads forming the stripes together with the threads defining the apertures.

I claim:

The ornamental design for woven mesh cloth as shown and described.

LOUISE BARNES GALLAGHER.
